United States Patent Office

Des. 199,104
Patented Sept. 8, 1964

199,104

SUPersonic AIRCRAFT

William C. Sleeman, Jr., Newport News, Va., and
Thomas A. Toll, Lancaster, Calif., assignors to the
United States of America as represented by the Na-
tional Aeronautics and Space Administration

Filed July 11, 1963, Ser. No. 75,758

Term of patent 14 years

(Cl. D71—1)

(Granted under Title 35, U.S. Code (1952), sec. 266)

FIG. 1

FIG. 2

FIG. 4

FIG. 3

FIG. 5

FIG. 6

FIG. 1 is a top perspective view of the supersonic aircraft embodying our new design;

FIG. 2 is a top plan view thereof;

FIG. 3 is a side elevation thereof;

FIG. 4 is a front elevation thereof;

FIG. 5 is a bottom plan view thereof; and,

FIG. 6 is a rear view thereof.

The invention described herein may be manufactured and used by or for the Government of the United States of America for governmental purposes without the payment of any royalties thereon or therefor.

We claim:

The ornamental design for a supersonic aircraft, as shown and described.
